DESIGN FOR A WATCHCASE

Benjamin S. Katz, Cincinnati, Ohio, assignor to
The Gruen Watch Company, Cincinnati, Ohio,
a corporation of Ohio

Application November 6, 1936, Serial No. 65,732

Term of patent 7 years

To all whom it may concern:

Be it known that I, Benjamin S. Katz, a citizen of the United States, residing at Cincinnati, in the county of Hamilton and State of Ohio, have invented a new, original, and ornamental Design for a Watchcase, of which the following is a specification, reference being had to the accompanying drawing, forming a part thereof.

In the drawing:

I claim:

The ornamental design for a watchcase substantially as shown.

BENJ. S. KATZ.
